CLAIM

The ornamental design of headgear, as shown and described.

DESCRIPTION

FIG. 1 is a perspective view of headgear for use with a respiratory mask assembly according to my new ornamental design;

FIG. 2 is a front view thereof;

FIG. 3 is a rear view thereof; and,

FIG. 4 is a bottom view thereof.

The headgear shown in FIGS. 1-4 is shown in its pre-use condition. The headgear is designed to wrap about the head of a patient in use.

The broken lines show environment or structure, are for illustrative purposes only, and form no part of the claimed design. The dotted lines represent the border between claimed and unclaimed subject matter and form no part of the claimed design.
